UNITED STATES PATENT OFFICE.

CARL FUNKE, OF ESSEN, GERMANY, ASSIGNOR TO FRIED. KRUPP, OF SAME PLACE.

RAPID-FIRING GUN.

SPECIFICATION forming part of Letters Patent No. 623,895, dated April 25, 1899.

Application filed December 20, 1898. Serial No. 699,800. (No model.)

To all whom it may concern:

Be it known that I, CARL FUNKE, a citizen of the German Empire, residing at Essen, Germany, have invented certain new and useful 5 Improvements in Rapid-Firing Guns, of which the following is a specification.

My invention has reference to improvements in rapid-firing guns with a cradle and a shoulder-piece for pointing; and it consists, 10 essentially, in means for automatically maintaining the elevation of the gun during the recoil and running-out movement of the barrel.

In guns supported in a cradle in which the barrel has a motion back and forth the position of the gravity of the moving mass is changed. This change does not affect guns provided with elevating mechanism, but it affects guns pointed by a shoulder-piece, inasmuch as in firing the gun the gun and cradle have a tendency to settle at the rear end, whereby the elevation of the gun is changed. To counteract this effect of firing, it is desirable to provide means for automatically maintaining the elevation of the gun during the 25 recoil and running-out movement. I accomplish this by providing the shoulder-piece with a clutch automatically clamping the cradle to the carriage at the commencement of the recoil and releasing the cradle during the 30 last part of the running-out movement.

The nature of my invention will best be understood when described in connection with the accompanying drawings, in which—

Figure 1 represents a side elevation of part 35 of a gun embodying my invention, the gun being in firing position and the clutch released. Fig. 2 is a side elevation of the principal parts of Fig. 1, the clutch being in the position for recoil and running-out movement. Fig. 3 is a plan view of Fig. 1, partly 40 in section. Fig. 4 is a vertical section on the line 4 4, Fig. 1.

Similar letters of reference designate corresponding parts throughout the several views 45 of the drawings.

Referring to the drawings, the letter *k* designates the gun-carriage; *g*, the cradle; *h*, the shoulder-piece, fastened to the left cheek of the cradle. In firing, the gun-barrel runs 50 back and then forward within the cradle, the trunnions of which are supported on the car-

riage. The shoulder-piece *h* has a slot *m*, within which one part of the clutching device (the cam *a*) is held by a bolt *b*. The cam *a* has two teeth *i i'*. *f* is a finger secured on the gun-barrel, which finger in the firing position of the barrel projects into the space between the two teeth *i i'*, Fig. 1. The second part of the clutching device (the clutching-sector *d*) is fastened to the carriage *k* by bolt *e*. This 60 clutching-sector *d* is concentric to the trunnions of the cradle and extends into and through the slot *m* of the shoulder-piece. The inner concave face of the sector *d* abuts against the forward end wall of the slot *m*. 65

The clutching-cam *a* has a jaw-piece *l*, with a wedge-shaped groove eccentric to the bolt *b*, adapted to be pressed against the wedge-shaped rear face of the sector *d*.

When the clutching-cam *a* is in the position shown in Fig. 1, the jaw *l* is not in contact with the clutching-sector *d*. In this position the gun can be pointed to any desired elevation by means of the shoulder-piece. When, however, the clutching-cam *a* is turned 70 sufficiently to press the jaw *l* against the sector *d*, Fig. 2, only a force tending to turn the breech end of the gun upward could release the clutch. Such a force, however, does not come into action in firing. On the contrary, 75 the breech end has a tendency to be depressed, which will cause the jaw *l* to be more firmly pressed against the sector *d*. When the clutching-cam *a* is in the position shown in Fig. 2, the cradle, respectively the gun-barrel, and the 80 carriage are therefore coupled together in such a manner that the forces coming into action during firing cannot cause a change in the elevation of the gun. 85

Before firing the gun and the clutch are in 90 the positions shown in Fig. 1, when the gun may be pointed to any elevation by the shoulder-piece. When the gun is fired, it runs backward, and the finger *f*, acting against the tooth *i'*, turns the cam *a* on the bolt *b*, so 95 as to press the jaw *l* firmly against the sector *d*, while the finger clears the tooth *i'*, Fig. 2.

By the clutch the shoulder-piece, which is rigidly attached to the cradle, is clamped to the carriage through the sector *d*, so that the 100 cradle cannot turn on the carriage—that is, the elevation of the gun is maintained. To-

ward the end of the running-out movement the finger *f* strikes the tooth *i* and turns the cam *a* back into the position Fig. 1.

It is evident that the details of the clutch 5 may be varied or that any other suitable friction device may be substituted therefor.

What I claim as new is—

1. In a rapid-firing gun, the combination 10 with the gun-carriage, the cradle and the barrel of the gun, of a shoulder-piece secured to the cradle; a clutch interposed between the shoulder-piece and the carriage; a clutch-cam pivoted within the shoulder-piece and provided with teeth *i* *i'*; and a finger *f* attached 15 to the gun and engaging said teeth, for automatically throwing the clutch into action at the commencement of the recoil, and releasing it toward the end of the running-out movement, substantially as and for the purpose specified.

2. In a rapid-firing gun, the combination 20 with the gun-carriage, the cradle and the barrel of the gun, of a shoulder-piece *h* secured

to the cradle; a clutch interposed between the shoulder-piece and the carriage; said clutch consisting of a sector *d* concentric to the trunnions of the cradle, attached to the carriage and bearing against the forward end of a slot *m* in the shoulder-piece *h*, and a clutch-cam *a* with a jaw *l* pivoted within the slot *m*; and a finger *f* attached to the gun-barrel, adapted to engage a tooth *i'* during the first part of the recoil, so as to turn the cam *a* and force the jaw *l* against the sector, thereby locking the cradle to the carriage, 35 and to release the clutch during the last part of the running-out movement by acting against the tooth *i*, substantially as described.

In testimony whereof I have hereunto set my hand in the presence of two subscribing 40 witnesses.

CARL FUNKE.
